CHARLES STODDARD, OF HANCOCK, NEW YORK.

Letters Patent No. 63,576, dated April 2, 1867.

IMPROVEMENT IN SLEIGH-RUNNERS.

The Schedule referred to in these Letters Patent and making part of the same.

TO ALL WHOM IT MAY CONCERN:

Be it known that I, CHARLES STODDARD, of Hancock, Delaware county, New York, have invented a new and useful Improvement in Sleigh-Runners; and I do hereby declare that the following is a full, clear, and exact description thereof, which will enable others skilled in the art to make and use the same, reference being had to the accompanying drawings, forming part of this specification.

Figure 1 is a side view of my improved sleigh-runner.

Figure 2 is a vertical cross-section of the same, taken through the line and fig. 1.

Figure 3 is a vertical cross-section of the same, taken through the line y y , fig. 1.

Similar letters of reference indicate corresponding parts.

My invention has for its object to so improve the construction of sleigh-runners that the shoe may be held firmly and securely in place, even should it become broken while in use; and it consists in forming the runner in two parts, with a dove-tailed groove formed in and between them, and in forming the shoe with a central projecting dove-tailed flange fitting into the dove-tailed groove in the runner, the whole being constructed and arranged as hereinafter more fully described.

A and B are the parts of the runner, which are made with angular longitudinal notches or grooves upon their inner sides, which, when the said parts A and B are put together, form a dove-tailed groove in the face of the runner, as shown in figs. 2 and 3. C is the shoe, which is made with a dove-tailed flange, c', formed upon the centre of its upper side, which fits into the dove-tailed groove formed in the parts A and B of the runner. The parts A and B of the runner, and the shoe C, are all secured to each other by bolts, D, and nuts, E. The bolts D pass through holes in the parts A and B, and through holes or notches in the flange c', as shown in the drawings. The flange c' need not extend quite to the rear end of the shoe C, so as to leave a space for the rear end of the parts A and B to descend in the rear of said flange in the form of a cap for the purpose of still further securing the said shoe. The shoe C may be made in one piece or in section, as may be desired, but I prefer to make it in one piece, as producing less friction in passing over the road.

I claim as new, and desire to secure by Letters Patent—

1. Forming the sleigh-runner in two parts, A and B, with a dove-tailed groove formed in and between them, substantially as herein shown and described, and for the purpose set forth.
2. Forming the shoe C with a central projecting dove-tailed flange, c', substantially as herein shown and described, and for the purpose set forth.

The above specification of my invention signed by me this 31st day of December, 1866.

CHARLES STODDARD.
